UNITED STATES PATENT OFFICE.

LOUIS KLOPSCH, OF NEW YORK, N. Y.

BASE FOR STEREOTYPE-PLATES.

SPECIFICATION forming part of Letters Patent No. 360,307, dated March 29, 1887.

Application filed March 11, 1886. Serial No. 194,762. (No model.)

To all whom it may concern:

Be it known that I, LOUIS KLOPSCH, of New York city, in the county and State of New York, have invented a certain Improvement in Bases 5 for Stereotype-Plates, of which the following is a specification.

The improvement is intended more particularly for serving with plates of celluloid or analogous tough and durable material of such 10 light weight as to render practicable their transmission to distant points by mail; but it may serve with great advantage with type-metal or any other stereotype.

I use the term "stereotypes" to indicate 15 plates of any material adapted to be printed from, and of such thickness or height as to require to be supported on bases in order to render them type-high. The supports or bases may obviously be of any weight and cost, as 20 one set of bases may serve with a great number of different plates successively applied and removed.

In order to facilitate the fastening of the 25 plate to the base, I provide grooves on the upper side of the base and secure therein a material—as soft metal or wood, or both—adapted to receive and hold nails; and I indicate on the plate by a series of indentations or depressions the location of these grooves thus 30 filled. Nails driven through at these points will find in the base suitable material to receive and hold them, while the adjacent portion of the base will serve to efficiently support the plate without being anywise disturbed 35 or distorted by the operation.

In what I consider the best means of carrying out the invention I produce the body of the base or support in cast-iron, and after finishing it to proper size plane longitudinal and 40 transverse grooves in it of dovetail section. In each longitudinal groove I afterward hold a stick of wood of smaller section and pour in melted lead to fill the space between. This affords a very desirable construction for receiving and holding the nails. I also provide for further locking the lead in the base by allowing it to flow into holes drilled or otherwise produced transversely to the groove. 45

The accompanying drawings form a part of 50 this specification and represent what I consider the best means of carrying out the invention.

Figure 1 is a cross-section. Fig. 2 is a plan

view. A portion of the stereotype-plate is removed to show the base. Fig. 3 is a plan of the base before the grooves have been filled. 55 Fig. 4 is a section on the line xx in Fig. 3. Fig. 5 is a section taken on the line yy of Fig. 3. Fig. 6 is a cross-section of the completed base with the stereotype-plate and column-rules in place. Fig. 7 is a corresponding view, 60 the line of section being taken through one of the cross grooves. Fig. 8 is a cross-section. It shows a modification.

Similar letters of reference indicate corresponding parts in all the figures where they 65 occur.

A is the hard portion or main body of the base. It is of proper height to hold the printing-surface of the stereotype-plate B type-high. In each face are three longitudinal 70 grooves or scores, $a a a$, and through its substance are a series of holes, $a' a'$, across the grooves $a a$, and communicating with each. There are also a series of corresponding transverse grooves, a^2 . The grooves a and a^2 are 75 filled with soft material. The holes a' are also filled or partly filled, as will presently be explained. They are serviceable in allowing the soft material to flow out into them and form arms which lock the soft material in the base. 80 C C are column-rules.

D D are nails driven through the plate B into the soft material M in the grooves $a a a$.

To make the base, cast the main body A of rectangular section, and plane or mill it to the 85 exact form and size required. At the same or a subsequent operation, as by treatment by a suitable planer, produce the longitudinal dovetail grooves $a a a$. Either before or after this, drill the cross-holes a' . Then, carrying each 90 base separately or a number together mounted transversely on the planer-table, produce a series of corresponding transverse grooves, a^2 . Then, after heating the part A nearly to the temperature of melted lead, hold in suitable 95 close-fitting metal clamps and introduce in each groove a smaller stick of soft wood, P, and, holding it in place by means analogous to the chaplets used to hold cores in place in iron casting, pour in melted lead to fill the 100 space around and over each stick. This operation fills the grooves $a a a$ with wood, P, and lead, M, and the transverse grooves a^2 with lead, M*, alone. It also fills the whole or a portion

of each hole a' with lead, forming in each an arm, M' , cast in one with the lead, M . There should be a surplus of lead. When all is cooled, use a shaving-machine to remove such lead as 5 is in excess of the requirements, and which cannot be readily otherwise removed with sufficient smoothness, and the base is complete.

To use the base, apply the plate B thereon and drive nails D through into the lead, M , and 10 wood, P . Print as usual, and after the job is finished pull off the plate, and thereby draw out the nails. After each use the holes in the lead at the top may be partly filled up by 15 gentle hammering, if desired. It is not important to do more than simply flatten down any burrs which the insertion and withdrawing of the nails may have raised.

The entire base may be reversed and either 20 face used uppermost. This allows the nails to be driven and withdrawn many times before the soft material is seriously damaged.

At long intervals the whole base may be put 25 in the melting-pot and the lead melted out, after which it may be refilled, using the same lead and either the same or new wood. It will again serve as before. The sticks can be omitted, if preferred, and the lead, M , may entirely fill each groove. Nails can be easily 30 driven into lead and will hold well therein.

The lead is retentive, and a small number of 35 nails will hold large surfaces of stereotype-plates.

In applying the parts together and fastening them, the column-rules C are of service 40 in holding the plates exactly in position. The nails D may be driven in the usual manner.

Screws or other like fastenings may be used 45 in place of nails D , if preferred.

Modifications may be made in the forms and 50 proportions of the base without departing from the principle or sacrificing the advantages of the invention. Two grooves a , or even one, may serve instead of three. Four or a larger number may be used. They may be made on one face only of the base; but in such case the base will not be reversible. If only one groove is used, it should extend along the middle of the column. The grooves may run longitudinally alone or transversely alone. Other soft metal than lead may be used. The 55 grooves may be of rectangular section instead of dovetailed, depending on the engagement of

the metal in the holes a' alone to secure it. The adhesion of the soft metal to roughened sides of the grooves may be sufficient to hold it reliably without the arms M' engaging in the holes a' . Wood alone or certain gums may be used with some success for the soft material in the grooves. In such cases pins of hard wood or other strong material should be driven 60 transversely through the holes a' .

The holes a' may be only partly filled in consequence of the lead chilling if the bases are not sufficiently warmed. It is sufficient if the lead flows into the hole only a little way. I prefer 65 the whole as first described.

It will be observed that I do not intend to embrace within this case a construction for bases for stereotype-plates where a metallic support is provided with parallel rabbets into 70 which are introduced removable strips of wood or other soft material in such a manner that the upper surfaces of the wooden strips may be on a level with the upper surface of the support and the stereotype-plates are secured to the 75 wooden strips, since this construction has been made the subject of a separate application by me for Letters Patent, filed December 7, 1885, Serial No. 184,892.

I claim as my invention—

1. A stereotype-plate, B , hard supporting-base A , and nails or equivalent fastenings D , in combination with each other and with a filling, M , of soft material, and locking-arms M' , fitting in corresponding recesses in the base, as herein 85 specified.

2. The wood strip P , lead envelope M , and locking-arms M' , in combination with each other and with a correspondingly-recessed hard base, A , adapted to serve with a stereotype- 90 plate, B , and nails D , as herein specified.

3. A longitudinal soft material, M , in combination with the transverse soft material M^* , hard base A , plate B , nails D , and means, as the locking-arms M' , for confining the filling in the 95 base, as herein specified.

In testimony whereof I have hereunto set my hand, at New York city, New York, this 5th day of March, 1886, in the presence of two subscribing witnesses.

LOUIS KLOPSCH.
